United States Patent Office

Des. 183,512
Patented Sept. 16, 1958

183,512

ANCHOR DAVIT

Roy L. Fyock, Roanoke, Va.

Application September 4, 1957, Serial No. 47,609

Term of patent 7 years

(Cl. D71—1)

Fig.1

Fig.2

Fig.3

Fig.4

Fig.5

Figure 1 is a perspective view of an anchor davit showing my new design, illustrating the davit in position for use;

Figure 2 is a side elevational view thereof in the raised position, shown in Fig. 1;

Figure 3 is a top plan view of the anchor davit in folded position;

Figure 4 is a side elevational view thereof in the folded position shown in Fig. 3; and

Figure 5 is an end elevational view taken from the right of Fig. 4.

I claim:

The ornamental design for an anchor davit, as shown.
